TOY FLYING PLATFORM PILOT

Norman S. Gardner, Brooklyn, N. Y.

Application November 8, 1957, Serial No. 48,388

Term of patent 3½ years

(Cl. D34—15)

Fig. 1 is a front view of a toy flying platform pilot, showing my new design.

Fig. 2 is a rear view thereof.

Fig. 3 is a cross-sectional view taken on line 3—3 of Fig. 1.

Fig. 4 is a cross-sectional view taken on line 4—4 of Fig. 1.

I claim:

The ornamental design for a toy flying platform pilot, substantially as shown.
